ANIMATED DISPLAY DEVICE

John De Witt Gray, Chicago, Ill.

Application June 12, 1933, Serial No. 675,426

10 Claims. (Cl. 40—126)

My invention relates to animated display devices and more particularly to devices for producing a fluid flow illusion for advertising purposes.

5 An object of the invention is to provide devices of this type which are simple and economical to manufacture and effective and efficient in operation.

Other objects and advantages will appear from 10 the following description taken in conjunction with the accompanying drawing, in which

Fig. 1 is a front elevation partly in section of a device embodying the invention;

Fig. 2 is a sectional detail view of an agitator 15 embodied in the invention; and

Fig. 3 is a plan view of the pump taken on line 3—3 of Fig. 1.

Referring now more in detail to the drawing, a vessel or container 5 is provided having a cup-shaped cover 6 for receiving the liquid flowing 20 downwardly on the outside of a tube 7 of brass or other suitable material. The liquid accumulates in the cup and drains downwardly through an aperture 8 into the vessel 5.

25 The lower end of tube 7 extends into a small rotary pump 9 of a well known construction which is submerged in the liquid in the vessel and forces liquid into the tube and upwardly into a bottle 11 or other suitable receptacle. From the bottle 30 the liquid flows downwardly over the tube and conceals the tube, giving rise to the illusion that the bottle is suspended in the air with a constant flow of liquid issuing therefrom. The upper end of the tube is bent at an angle and is secured to 35 a resilient collar 12, which serves to support the bottle on the tube.

The liquid used in the device is preferably an oil or a liquid having an oil base. This makes it 40 possible to submerge the pump directly in the liquid without taking any particular precautions to prevent leakage from the pump, as around the shaft or tube since any leakage from the pump will remain in the system. The pump may be driven by a small electric motor 13 of the synchronous type, such as used in electric clocks. The pump is attached directly to the motor by the 45 drive shaft 14 and a support 15. The motor itself is secured to the underside of the cover 6 by a support 16. Thus when the cover is removed from the vessel, the motor and pump are also removed therewith, making it simple to inspect and repair the device.

In order to enhance the illusion and prevent 50 the liquid from flowing from the bottle in too smooth a stream, an agitator 17 is provided in the

bottle to break up the evenness of the flow as the liquid leaves the bottle. This agitator may comprise a small paddle wheel rotatably mounted in the collar 12. The outgoing liquid strikes the 5 paddles of this wheel, causing the wheel to rotate and agitate the liquid.

It will be understood that the nature and embodiment of the invention herein described and illustrated is merely a convenient and useful form of the invention and that many changes and 10 modifications may be made therein without departing from the spirit and scope of the invention.

I claim:

1. In a display device, a vessel for receiving a 15 liquid to be circulated, a cover therefor, a motor and pump secured to the bottom of the cover, said motor being positioned above the liquid in said vessel and the pump extending into said liquid, a tube extending through the cover and into said pump, and a receptacle at the upper end of said tube for receiving liquid from said tube and discharging the liquid over said tube.

2. In a display device, a vessel for liquid, a pump submerged in the liquid in said vessel, a tube 25 extending upwardly from said pump, a receptacle-like cover for said vessel through which said tube extends, and a receptacle at the upper end of said tube for returning liquid over said tube into the receptacle-like cover.

3. In a display device, a vessel for receiving a 30 liquid, a cup-shaped cover therefor having an aperture communicating with the vessel, a motor secured to the under side of said cover above the liquid, a pump secured to the motor and extending into the liquid, a tube extending upwardly from the pump and through said cover, and a receptacle at the upper end of said tube for receiving liquid from the tube and discharging it over the tube into said cover.

4. In a display device, a vessel for liquid, a pump submerged in the liquid in said vessel, a tube 40 extending upwardly from said pump, a receptacle-like cover for said vessel through which said tube extends, a receptacle at the upper end of said tube for returning liquid over said tube, and means for supporting said receptacle on said tube.

5. In a display device, a vessel for liquid, a pump submerged in the liquid in said vessel, a tube 50 extending upwardly from said pump, a receptacle-like cover for said vessel through which said tube extends, a receptacle at the upper end of said tube for returning liquid over said tube, and means for supporting said receptacle on said 55 tube.

tube, comprising resilient means engaging said receptacle.

6. In a display device, a tube, means for forcing liquid through said tube, a receptacle at the upper end of the tube for receiving liquid from the tube and discharging it over the tube, and means in said receptacle for agitating the liquid to break up the evenness of the stream leaving the receptacle.

10. 7. In a display device, a tube, means for forcing liquid through said tube, a receptacle at the upper end of the tube for receiving liquid from the tube and discharging it over the tube, and means actuated by the liquid for agitating the stream of liquid leaving the receptacle.

8. In a display device, a tube, means for forcing liquid through said tube, a receptacle at the upper end of the tube for receiving liquid from the tube and discharging it over the tube, and 15 rotatable means actuated by the liquid for agitating the stream of liquid leaving the receptacle.

20

9. In a display device, a vessel for liquid, a pump submerged in the liquid in said vessel, a tube extending upwardly from said pump, a receptacle-like cover for said vessel through which said tube extends, a receptacle at the upper end of said tube for returning liquid over said tube into the receptacle-like cover, and means actuated by the liquid for agitating the stream of liquid leaving the receptacle.

5

10. In a display device, a vessel; a quantity of oil in the vessel, a pump submerged in said oil, a tube extending upwardly from said pump, a receptacle at the upper end of said tube for receiving oil from the tube and discharging it over the tube, a paddle wheel in said receptacle actuated by the oil for agitating the stream of oil leaving the receptacle, and a dished cover for said vessel for receiving the oil moving downwardly over said tube.

15
